achusetts

Application December 2, 1940, Serial No. 368,206

10 Claims. (Cl. 221—95)

My invention has to do with improved hose handling apparatus particularly adapted for mounting on a service station dispensing "pump." The so-called "pump" commonly includes many apparatus elements closely packed in a display casing. Real effort has been made to give a good appearance to the display casing. The casing is needed, like the body of an automobile, to protect the mechanism covered by it. Since the casing is what the public sees, its appearance is particularly important. The appearance of anything mounted on the pump casing is likewise important. In this art much effort has recently been made to produce improvements in the dispensing hose and hose handling apparatus for these dispensing pumps. It is this kind of improvement to which my invention is directed.

Ordinarily the hose, about ten feet long with a delivery nozzle about twenty inches long at the end, is hung in a single loop outside and on one side of the pump casing. This hose length is about the limit that can be neatly and simply hung in one loop outside the pump casing. The pump casing is not high enough to carry much more hose mounted on it in that simple, neat-appearing manner.

The problem arises when substantially more than the ten feet of dispensing hose is wanted. In various ways the extra hose length has been provided in prior art devices. One way is to removably store extra hose length inside the pump casing. My particular problem arises when there is not room in the pump casing to store extra hose length desired for use. For example, I may desire to use the same size and style of pump casing to contain apparatus for dispensing gasoline and apparatus for dispensing Diesel engine oil. The mechanism desired for the latter apparatus takes up more room in the casing than does the apparatus for dispensing gasoline. The general reason is the higher rate of delivery wanted for Diesel engine fuel. Therefore, larger parts are put in the same size casing. There is then no room to handle extra hose length in the casing with apparatus for dispensing Diesel engine fuel. This is just one specific example of a circumstance in which my invention is particularly useful. It is for such circumstances that my particular disclosure has been designed. It will satisfy similar needs for dispensing pump use.

The invention in this and other aspects will be disclosed in sufficient detail by the accompanying drawings and the description of them.

Fig. 1 is a side view of the dispensing apparatus with the hose hung at one side of the casing, all as it appears, ready for use;

5 Fig. 2 is a section on line 2—2 of Fig. 1 but omitting the showing of apparatus inside and of the hose outside the casing;

Fig. 3 is a view with the lower part of the pump casing cut away, indicating a modified arrangement;

10 Fig. 4 is a sectional view on line 4—4 of Fig. 5;
Fig. 5 is a central section of Fig. 1 with parts cut away; and

15 Fig. 6 is a detail sectional view of some parts shown in the arrangement of Fig. 5 and including other parts not shown in Fig. 5.

As shown in the drawings, see Fig. 5, for the purpose of illustrating a specific use of the invention, the hose handling apparatus is arranged as a conversion unit. That is, the "pump" casing, with operative parts inside (most of which are not shown), is indicated as it is used in a prior art commercial form of widely used "pump" but modified enough to adapt the casing for use with the improved hose handling apparatus. In this arrangement, without materially changing the "pump," I provide for combination with it, elements of my improved hose handling apparatus. As will be explained, one use of the apparatus disclosed specifically is for a hose turret conversion unit. The "pump" of the prior art may be made at the factory or taken as found already in use in the field and with little trouble and a little modification in its structure be adapted for incorporating my improved hose handling apparatus. In this sense I have disclosed a hose turret conversion unit for prior art "pumps." With it I can convert a prior art "pump" having old-fashioned hose handling apparatus to one having my improved hose handling apparatus, conveniently, with relatively small expense, and with full regard for the external appearance of the "pump." The structure as disclosed in the drawings is particularly adapted for adding my improvement at the factory assembly line to what are essentially standard forms of "pumps" or to such "pumps" by conversion of "pumps" already in the field.

50 The main casing of a prior art "pump" is indicated in Fig. 2. It has side panels 3 fastened to corner posts 5. On the latter, most elements of the "pump" apparatus are mounted, all as is very well known. At the top, the casing ordinarily has a decorative cover, wall, or hood joining the side walls. The hood is frequently made with a central pedestal to hold a light.

In my casing structure the top wall or hood 4 is joined to the side walls 3 as in the prior art. At its inner edge it has the large central opening 1, see Fig. 5. Around this opening is mounted the annular platform 2, on which base casting 6 of my turret construction rests. This casting is suitably bolted at several points, as at 7, to the inner edge of platform 2. The platform is supported by an annular skirt 8 extending to corner posts 5 and there fastened for support as by fasteners 8'. The skirt underlies hood 4 in overlapping position. An annular depression 9 in the hood underlies an annular sheathing plate 10 between the platform 2 and the hood 4, the appearance generally being as if the hood extended to the platform. The inner margin of plate 10 rests on the platform 2 and a packing 11 is placed between the plate 10 and the casting 6. Thus, the turret base casting is mounted in the hood opening in the fashion of a hydrant and is supported from the corner posts, all with neat, simple appearance at this connection of the turret through the top or hood of the pump casing.

The casting 6 has a central bowl 12 extending down far enough to make an inside pipe connection 30 with the liquid supply discharge pipe 31. This pipe 31 is usually directed to a point in the side of the casing wall but is here directed, as shown, to a central point in the top of the casing. The bowl has an upwardly extending and rotatable outlet pipe 13 for the liquid. Pipe 13 rotates in bearings mounted in turret support or hollow frame 14 resting on casting 6 to which it is bolted with gasket between as at 15, and other like bolts. The bearing plug 16 is screwed in at the bottom. The pipe collar 17, rigidly but detachably fastened as indicated, bears against the under side of plug 16 and acts as a thrust bearing against upward movement of the pipe in the turret movement. Pipe 13 rotates with turret casting 18, being threaded in at the bottom.

I provide a special structure and arrangement to guard against leaks of the inflammable liquid fuel along the outside of the rotatable discharge pipe section 13. The stationary part of the turret pedestal frame 14 is hollow. It supports the two spaced bearings 19 and 20, the latter being the plug. These bearings are conveniently made of brass composition bearing metal. On the top side of the lower one and the bottom side of the upper are two steel cups 20. Each contains an annular ring 21 of molded rubber composition suitable for packing. Outside of each ring is a metal follower plate 22. Between these plates is a coiled spring 23. When the parts are assembled on the pipe as shown, and the plug 16 screwed home as indicated, the spring is effectively compressed. Then the constantly applied spring force urges the packing rings into sealing contact with the rotatable pipe.

As an additional safeguard against leaks out of space 24 and along the rotatable pipe to the atmosphere I provide a special liquid drain from this space. It is shown in Fig. 6. Small cored passage 25 leads from the bottom of space 24 through parts 14 and 8 to pipe 26. The latter has a drain pipe connection to the sump chamber 27 of the air separator. Such chamber is connected to the atmosphere by vent pipe 28. When the pump is running, a float valve connection 29 with the suction side of the pump prevents filling a sump chamber 27 full. When the pump is idle, the sump chamber has sufficient capacity to hold all the liquid that can possibly drain

into it from pipe 26. Thus, no liquid from any leak past the rotatable pipe, located as shown near the top of the system, can ever unintentionally pass out to the atmosphere where vent 28 opens at the hole where the hose nozzle end is usually stuck in from its support. On the contrary, liquid from any such leak is drained back to the air separator. From it such liquid is taken again into the pump at the suction side. Thus, if liquid leaks, it is merely circulated through a by-path to join again the main stream.

The arrangement just described, in the special environment, is a detail feature. It is particularly important and useful for this reason: One of the difficulties in providing a turret arrangement for passing inflammable liquids through the top of a pump casing to a dispensing hose is the danger due to leaks. Where the pipe connections rotate, such liquids tend to creep along the bearings. The latter of course tend to wear. The problem of packing the rotatable joints is important. Even when that problem is given every possible attention there is the further problem to add insurance against the results of leaks. My special means takes care of both these problems. The result is that some obvious objections to using a turret top delivery piping system to feed a flexible delivery hose are avoided.

As mentioned above, pipe 13 rotates with turret casting 18, into which the pipe is threaded. Casting 18 has a lower projection extending into opening 32 of the table support 14 to form a bearing between frame and casting. A ball race 33 in the top of the frame supports the casting 34 for its rotation. A skirt 34 is attached to the annular projection 35 around the base of the casting and covers frame 14 with a relatively rotatable enclosing wall.

The inlet passage into the chamber of turret bowl 18 is provided with threaded nipple 36 which extends from the passage to the liquid whirling means 37. Liquid discharged into the center of the whirling means 37 is deflected by the curved blade 38 (Fig. 4). This gives to the liquid a rotary movement in the turret bowl. Such flow movement of liquid is made visible through glass wall 40, the visibility being aided by the stub post 39 as a background. All the details of the specific visible indicator are not described as such devices may take different forms and the indication of one will be understood in this art. The transparent cap or wall 40 of the turret top rests on an annular support 41 of the casting. Clamping member 42 is threaded on the support 41 and holds the lip 43 of wall 40 tightly on the support. Member 41 is bolted securely to the top of casting 18 as by bolts 44. Gaskets are fitted between connecting parts to give tight joints and insure against leakage.

Liquid is discharged from the bowl through outlet 48 to the flexible hose 49, the inner end of which is joined by coupling 50 threaded into the outlet. The hose hangs in a loop outside the casing, see Fig. 1, terminating in nozzle 51 which is placed on a nozzle support 52 at the side of a casing wall when not in use. To hold the hose loop nicely I prefer to have a hairpin-like, horizontally arranged hook 46. This is indicated on the side of the casing near the bottom, with the hose loop held by it.

In operation the nozzle is taken from its support and the hose carried to the dispensing point. By reason of the greater length of hose and the rotating turret chamber the dispensing range is

greater than that serviced by the usual ten feet of hose on the side of the ordinary pump. It is greater not only by the amount of hose added by one flight of the usual outside loop extending upwardly to the rotatable turret member 18, but also by reason of the rotation of the member itself. A central point of rotation permits a circular dispensing area with a radius substantially equal to the length of the hose itself or to the base of the angle made by the casing and the hose. With the ordinary "pump" generally in use at the present time the hose is attached to one side of the casing, thus restricting the service distance on the opposite side to materially less than the length of hose. The hose must bend around the casing to reach the dispensing point which not only shortens the effective length of hose but also increases hose wear. With the apparatus here disclosed the hose may be carried in any direction from the pump without necessarily bending it to reach the dispensing point. Thus, hose wear is a minimum, while a given length of hose is used with an increased effective radius of operation as compared to dispensing hose connected as in the prior art without the turret arrangement.

In the preferred embodiment of my hose handling apparatus the length of flexible hose used and height of turret are regarded as of some importance. A simple increase in hose length by itself will, of course, increase the dispensing range, yet, unless care is taken in disposing of the hose properly, a "pump" will acquire a sloppy appearance or be inconvenient for handling from the operator's point of view. Consequently, I prefer the turret high enough so the depending hose will clear the edge of the hood conveniently as the hose is carried around the casing in any direction and the turret bowl is rotated in ordinary dispensing operations. The hose is preferably that length which will bring the bottom of a loop substantially even with the base of the casing as in Fig. 1. The apparatus is then of neat appearance and will remain so. The operator is able to carry the hose in any direction conveniently without the annoyance of catching the hose on the casing hood or causing a worn spot on the hose or on the casing by such rubbing contact.

Another feature of my apparatus to be emphasized is the provision for one visible liquid discharge indicator as furnished by glass 40 which can be seen from any position around the casing. The transparent wall of the turret bowl with an indicator fixed centrally at the top takes the place of the two flow indicators commonly found in nearly all modern "pumps." These latter are at opposite sides of the casing and generally project a little from the casing walls so that the customer can have a visual indication of the flow of clear liquid through the system to the nozzle from most points at which he might be watching the operation. Having two such indicators involves a comparatively expensive apparatus for the liquid to be whirled for both indicators during dispensing.

In the modification illustrated in Fig. 3 the turret device is shown attached to a "pump" structure with no change in the casing itself. This form may be used in such instances of converting "pumps" already in operation at a station where the advantages gained by an increase in hose length and revolving turret are desired without going to the expense of changing the "pump" casing hood structure itself. The turret unit may be affixed by elbow piping 53 to the discharge pipe at the side of the casing from which the flexible

hose is usually hung in a loop. The turret extends above the pump casing and operates with the center of the dispensing radius at the side of the casing instead of being disposed centrally of the casing. The additional drainage line of Fig. 5 for leakage around the rotating pipe 13 of this form can follow the line of elbow pipe 53 to the casing and from there be connected to the air separator sump as above outlined, if this draining feature is wanted. In this Fig. 3 similar parts are primed as compared to Fig. 5. It will be understood that the hose is hung up when not in use as in Fig. 1, and the piping 53 emerges from the casing adjacent the hose nozzle support.

The foregoing description will enable a manufacturer of service station "pump" equipment to make and use the invention. The structure of the drawings is disclosed in considerable detail so far as the new features are concerned. Such detail can of course be varied widely within the range of their fair mechanical equivalents and the invention now disclosed can be embodied in various different forms. The improved equipment disclosed for a long dispensing hose on a service station "pump" will be found particularly useful in these respects. The long hose will be easy to use without tiring the operator; its full length will be available for service at any radius; its swiveled connection to the liquid supply is not likely to leak, but if it does, the leak is vented and the liquid returned to the supply system; and these new advantages are attained while a desired simple outside pump casing and hose neatness are retained.

The invention and its scope are pointed out in the following claims.

I claim:

1. In liquid dispensing equipment, the combination of a vertical casing, a long dispensing hose outside the casing, liquid supply means inside the casing, mechanism positioned at the top of the casing connecting the liquid supply means to the hose, said mechanism consisting of a rotatable turret member in the form of a bowl having a transparent wall therein to indicate its fullness of liquid and a wall through which the inner end of the hose is connected and carried, a support for said turret member having bearings for the members' rotation, a depending pipe fastened in the bottom of said bowl and rotatable therewith, bearing supports for said pipe, a stationary bowl member at the bottom of said rotatable pipe, the said liquid supply means having its discharge point in the latter bowl, said hose being long enough to reach a delivery point at a substantial distance from the base of the casing and adapted by rotation of said turret member to give delivery up to the limit of such distance and along any radius from the base of the casing.

2. The structure and arrangement of claim 1 in combination with a delivery nozzle at the outer end of the hose and a support for said nozzle near the upper end of the casing, the length of the hose being such that when the nozzle is mounted on its support the hose hangs in one loop alongside the casing with one flight of the loop extending upwardly for its connection to be carried by the rotatable turret member.

3. The structure and arrangement of claim 1 characterized by the addition inside the rotatable turret member bowl of liquid whirling means operable by pressure of liquid fed to the bowl from the said depending pipe in its bottom and indicating means adjacent the transparent wall of said bowl adapted to make the whirling of the liquid easily visible from the outside.

4. A long hose in combination with hose handling apparatus adapted for mounting on the casing of a service station pump to increase conveniently the dispensing range of such pumps for liquid fuel to automobiles, said apparatus consisting of a chambered pedestal frame member with means to clamp it centrally at the top so as to extend above the pump casing, a rotatable bowl with its base mounted on bearings and overlying the top of the pedestal frame, an enclosing wall mounted as a casing skirt to hide the pedestal frame and adapted to appear as a relatively short upward central extension of the pump casing, said rotatable bowl having means to connect with, support, and carry the inner end of the hose, means mounted on said bowl to indicate the presence and the flow of liquid therein the visual indicating part of said means being mounted at the top of said bowl, a pipe, with bearings in said pedestal frame, mounted to extend therethrough and rotate with said bowl, means at the bottom of said frame adapted to connect said pipe with the liquid supply from the dispensing pump, said hose handling apparatus combined with its long hose being adapted for mounting on a dispensing pump in the fashion of a hydrant extending centrally from the top of the pump casing.

5. A long hose in combination with hose handling apparatus adapted for mounting on the casing of a service station pump to increase conveniently the dispensing range of such pumps for liquids to automobiles, said apparatus consisting of a pedestal frame member with means at its base to clamp it in position centrally at the top so as to extend above the pump casing, a rotatable bowl mounted at the top of said frame, means to carry liquid from inside the pump casing through said frame and into said rotatable bowl, the latter having means to connect with, support, and carry the inner end of the hose, said bowl being adapted to move around bodily with its hose connection as the hose is pulled to reach a dispensing point, an enclosing wall to hide the pedestal frame and adapted to appear as a relatively short upward central extension of but narrower than the main pump casing, whereby the simple appearance of a pump casing may be retained and its dispensing range conveniently increased uniformly all around a service pump.

6. In liquid dispensing equipment, the combination of a hose and hose handling apparatus, said apparatus including a rotatable support for the inner end of the hose and adapted to follow the hose when the latter is moved to any radius line for dispensing over a maximum range with a given length of hose, said support having a chamber therein connected for liquid delivery to the hose, liquid supply means connected to said chamber, and means mounted in said chamber including a transparent wall portion of the chamber to indicate to the outside both the liquid fullness of the chamber and whether or not liquid is moving therethrough, all constructed and arranged for said rotatable support to serve as a hose carrying means and as part of a visible liquid discharge indicator during dispensing operations.

7. The combination of a dispensing hose and a visible liquid discharge indicator apparatus adapted to serve also as hose handling apparatus, said apparatus including a supporting means with bearings and a liquid passage therethrough, a rotatable chamber mounted in said bearings and fed by said liquid passage a flow indicating device in said chamber, the latter having a window to show the working of said device, said hose having a fitting at its inner end extending through the wall of said chamber whereby that end of the hose is rotatably mounted for a wide range of service while being fed from said chamber, the whole combination being adapted for attachment to a liquid dispensing apparatus and for use as the liquid discharge indicator and hose handling apparatus in dispensing operations.

8. In a display casing for liquid dispensing apparatus, the combination of a casing, a dispensing hose outside, and liquid supply means inside the casing, a rotatable hose feeding device mounted on the casing and carrying the inner end of the hose for rotation with it, and having a pipe also carried to rotate with such device and connected to feed the liquid to it from the supply means, bearings around said pipe to support said pipe for rotation, a liquid collecting chamber around the outer side of said bearings, and a vented return means for any liquid leaking past said bearings back to the liquid supply means for delivery with the main supply through the hose, all adapted to prevent liquid leaking outside the rotary mounted hose feeding device.

9. The combination of a liquid fuel dispensing hose and means to mount it on a dispensing pump, said means comprising a supporting member providing vertically spaced bearing supports, a rotatable pipe and bearings therefor mounted in said supports, oppositely disposed pressure packing members one around each bearing, an interposed compressed coiled spring between said members to constantly force them into functioning position, a hollow turret member rigidly connected to the top of said pipe to receive liquid from and rotate with it, said hose having its inner end connected by the turret member to said pipe, the turret member having a pipe fitting attachment to said hose end to carry the latter with it, the said combination of parts forming equipment adapted for attachment as a unit to a dispensing pump.

10. In a hose handling apparatus, a display casing, a short vertical casing-like extension projecting centrally from the top wall of the casing, a transparent cap member on the extension top, a rotatable section of said extension carrying said cap, flow indicating means inside said cap, a dispensing hose with its inner end mounted on said rotatable section, and liquid supply means inside the casing connected to feed said hose through said extension and cap member, whereby the hose may be carried around said casing as its inner end swivels with said cap and the flow to the hose is indicated through said cap.
